Joseph & Jaeguer.

ATTORNEY.

UNITED STATES PATENT OFFICE.

CHARLES JOSEPH, OF NEW YORK, N. Y., ASSIGNOR TO ROSE JOSEPH, OF SAME PLACE.

POCKET-BOOK.

SPECIFICATION forming part of Letters Patent No. 445,373, dated January 27, 1891.

Application filed July 31, 1890. Serial No. 360,453. (No model.)

To all whom it may concern:

Be it known that I, CHARLES JOSEPH, of the city, county, and State of New York, a citizen of the United States, have invented 5 certain new and useful Improvements in Pocket-Books, of which the following is a specification.

This invention has reference to a pocket-book of that class in which, besides the usual 10 bill-pockets, a coin-pocket with an independent frame is arranged, said coin-pocket being so constructed that the same can open to a greater extent, so as to get at the coin in the same with great facility, while the dropping 15 of the coin from the pocket is fully prevented; and the invention consists of a pocket-book provided with a coin-pocket the frame of which is applied to a flange stitched to the gussets of the coin-pocket, while the lining of 20 the same is extended upward above the exterior gusset, so as to form a guard-flap, that extends from one corner of the frame to the other on or approximately on a line with the top of the frame, said guard-flap being folded 25 in between the jaws of the frame when the same is closed.

In the accompanying drawings, Figure 1 represents a perspective view of my improved pocket-book, showing the same in open position. Fig. 2 is a detail top view of the same, 30 also in open position, showing the mode of attaching the frame of the coin-pocket to the gusset of the same; and Fig. 3 is a vertical transverse section on the line 2 2, Fig. 2.

35 Similar letters of reference indicate corresponding parts.

Referring to the drawings, A represents a pocket-book, which is provided with a number of bill-pockets a and a coin-pocket B, 40 which is closed by an independent frame B', the hinged jaws of which are closed by a suitable locking device. For the purpose of forming a frame of larger size, whereby the coin-pocket B can be opened to a greater extent and access to the interior of the coin-pocket facilitated, a leather strip or flange d is stitched to the exterior gussets d' of the coin-pocket, said flange or strips d being used

for the purpose of applying the jaws of the frame of the coin-pocket thereto. The interior lining of the coin-pocket is so cut that the side walls of the same are extended from one corner to the other of the closing-frame of the coin-pocket, so as to form guard-flaps e, by which the coin is prevented from dropping out of the pocket, said flaps forming, when the coin-pocket is in open position, guard-walls that extend across both ends of the coin-pocket on a line, or nearly so, with the top of the frame, as shown in Fig. 1. The 50 guard-flaps e are folded in outward direction, so as to be folded up between the jaws of the frame, as shown in Fig. 3, they being thereby not in the way of the closing frame. In bags having sector-shaped gussets extending above 55 the top of the frame, such gussets prevent easy access to the coin and render the construction awkward and cumbersome.

My improved pocket-book has the advantage that by the use of the guard-flaps on a 60 line with the top of the frame the dropping of money from the coin-pocket is prevented, while a better appearance is imparted to the coin-pocket when the book is opened and the coins are easily accessible.

Having thus described my invention, I 70 claim as new and desire to secure by Letters Patent—

A pocket-book having an interior coin-pocket which is provided with a closing frame, 80 the hinged jaws of which are applied to the outwardly-bent strips or flanges stitched to the end gussets of the coin-pockets, and with a lining the side walls of which are extended from one corner of the closing frame to the 85 other on a line with the top of said frame, forming folding guard-flaps for the coin-pockets, substantially as described.

In testimony that I claim the foregoing as my invention I have signed my name in presence of two subscribing witnesses.

CHARLES JOSEPH.
